L. MILLER.

TORPEDO GUARD FOR SHIPS.
APPLICATION FILED JULY 12, 1917

1,247,439.

Patented Nov. 20, 1917.

2 SHEETS—SHEET 2.

UNITED STATES PATENT OFFICE.

LOUIS MILLER, OF BROOKLYN, NEW YORK.

TORPEDO-GUARD FOR SHIPS.

1,247,439.

Specification of Letters Patent. Patented Nov. 20, 1917.

Application filed July 12, 1917. Serial No. 180,178.

To all whom it may concern:

Be it known that I, LOUIS MILLER, a citizen of the United States of America, residing at Brooklyn, in the county of Kings 5 and State of New York, have invented certain new and useful Improvements in Torpedo-Guards for Ships, of which the following is a specification, reference being had therein to the accompanying drawing.

10 This invention relates to a torpedo guard or protector for ships, and the like, and has for its principal object the production of a simple and efficient guard, which may be conveniently held over the side of a ship, 15 in such a position as to permit the same to be immediately dropped in case of danger, to prevent the contact of a torpedo with the side of a ship.

Another object of this invention is the 20 production of a simple and efficient guard, which will constitute a yieldable buffer against which the torpedo may be abutted, when adjusted against a ship.

With these and other objects in view this 25 invention consists of certain novel combinations, constructions and arrangements of parts, as will be hereinafter fully described and claimed.

In the accompanying drawings:—

30 Figure 1 is a side elevation of the ship, showing the guard applied thereto, the guard being shown diagrammatically for the purpose of simplifying the illustration.

Fig. 2 is a vertical section through a portion 35 of the side of the ship, showing one of the sections of the guard in an extended position.

Fig. 3 is a section taken on the line 3—3 of Fig. 2.

40 Fig. 4 is a front elevation of one of the sections of the guard.

Fig. 5 is a transverse sectional view through a series of the guard sections.

Fig. 6 is a longitudinal section through 45 a portion of the hull of the vessel, showing the manner of attaching the guard section to the vessel.

Fig. 7 is a detail perspective of one of the joint connections, constituting the frame 50 for the guard section.

Fig. 8 is a front elevation of a portion of the yieldable guard net showing the manner in which the net is woven.

Fig. 9 is a top plan view, showing in diagram 55 the arrangement of the guard sections

extending around the end of a ship, such for instance as the bow or the stern of a vessel.

Fig. 10 is a longitudinal section through a portion of the hull of the vessel, showing a modified form of attaching the connecting 60 hooks on the torpedo sections to a hull of a wooden vessel, wherein reinforcing metallic plates are used.

Fig. 11 is a plan view of a portion of the 65 reinforcing frame for the net.

Fig. 12 is a top plan view of two of the 70 protector sections shown mounted upon the side of a ship.

By referring to the accompanying drawings by numerals, it will be seen that 1 designates the vessel, which may be of course of any suitable or desired construction, and the vessel 1 is adapted to support a plurality of protector or guard sections which 75 guard sections are adapted to be arranged in close relation to each other, and produce a continuous protector net, around the entire hull of the vessel. These protector sections comprise a frame 2, which frame is provided with a reinforced rear frame 3, and have the 80 longitudinally extending rods 4 of the protector frame, engaging the rear frame 3. The forward ends of the rods 4 are threaded into unions 5, which unions in turn receive the vertically extending brace pipe sections 85 6, for firmly holding the longitudinally extending rods 4 in proper spaced relation. Suitable transverse brace rods or pipe sections 7 are interposed between the lower unions of the protector sections, or frame 2, as is illustrated clearly in Fig. 3 of the 90 drawings. These unions 5 support upon their outer ends a plurality of outwardly extending brace rods 8, which brace rods 8 support a metallic frame 9 at their outer 95 ends, which metallic frame 9 is provided with suitable eyes 10 twisted therein, for fitting over the outer ends of the rods 8. Suitable ends 11 are threaded upon the rods 8 for firmly holding the frame 9 upon the 100 rods 8. This frame 9 is preferably formed rectangular, and a suitable net 12 is woven upon the outer frame 9, as is illustrated in Fig. 4, and in detail in Fig. 8. The net 12 is preferably formed of reinforced cable, 105 which is wrapped by a fabric wrapping, and which is thoroughly waxed to reduce friction to a minimum extent, and also to prevent the deterioration of the net, due to the chemical action of the water thereon. The 110

net 12 is formed of a plurality of looped portions 13, which fit around the outer frame 9, which looped portions are looped inwardly to produce inwardly extending loops 14, and 5 the net is then wound upon a strand for producing substantially diamond shaped pockets, as shown in Fig. 4, upon the face of the net. The strand is looped around the inner end of the loop 14, and is then passed over the 10 outer end of the loop 14, and is then wound around the strand 15, whereupon the outer end 16 of the strand passes over the loop 17 which is formed by winding the cable or strand around the inwardly extending loops 14. 15 By means of the wire net which is carried upon the outer end of the frame 2, it should be understood that a very yieldable construction is produced, by which a torpedo engaging the net, will merely impinge 20 against the surfaces of the net, and should the same enter in between the strands of the net, the flexible nature of the net will gradually force the torpedo from engagement with the net, due to the tightening action of 25 the net around the upper ends of the torpedo. The knotted connections at the junction of the substantially diamond shaped pockets formed by the net strands, will produce a very efficient connecting means and 30 allow a slight yieldable action of the pockets, but at the same time will assume a tightening action around an object which may try to penetrate between the strands. The formation of the outer end of the nose of a 35 torpedo will naturally cause a torpedo to work itself from engagement with the net due to the construction of the net.

An auxiliary or second net 6' is supported upon the top sections or rods 6 and 7, to 40 constitute a second line of protector net structures, and thereby prevent the passing of a torpedo through the protector members, should the first net be found defective, or should the first net be penetrated by the 45 torpedo. This second net 6' is formed similar to the first net 12, which has been described above in detail.

Each of these nets 6' and 12 are reinforced by means of a reinforcing net 12' whereby 50 the reinforcing net is formed of a plurality of strands carried by the frame 9, and the looped portions 17 of the net 12 are wound around the junctions 13' of the reinforcing net 12', such as is illustrated in Fig. 4 of 55 the drawings.

The net 12 as stated above is firmly secured to the outer frame 9, and the net is provided upon each side thereof with flaps or lips 18. These flaps are adapted to over- 60 hang the space between the next adjoining sections of the protector mechanism, and these sections will be termed the auxiliary sections 19, as shown in Fig. 5. The auxiliary section is formed similar to the first 65 section described, with respect to the frame

2, with the exception that the auxiliary section 19 is not provided with the extending flap 18. This structure is clearly shown in Fig. 5.

The lip or flap 18 which is formed upon each side of the net 12 is reinforced around its edge by means of a reinforcing frame 18', which reinforcing frame 18' is adapted to hold the flap or lip 18 in a proper position, so as to extend laterally of the main net 12. 75 This reinforced frame 18' is adapted to prevent the lip or flap 18 from swinging from side to side and becoming twisted due to the action of the water.

Each of the protector sections is similarly 80 connected to the hull 1 of the ship and each section carries a plurality of eye bolts 20 upon the rear frame 3 thereof, which eye bolts 20 engage the hooks 21, which are supported in any suitable manner upon the hull 1 of the vessel. Where a metal vessel is used, the hooks 21 may be secured thereto by passing the hooks through the hull 1 of the vessel and riveting the same, as shown in Fig. 6. Where a wooden vessel is used, such 85 as indicated by the numeral 1^a, the hooks 21^a may be passed through the reinforcing plates 22, as shown clearly in Fig. 10 of the drawings. These protector sections are adapted to have the eye portions 20 inserted over the 90 hooks 21 by moving the sections laterally as will be obvious by considering Fig. 6, and in order to hold these sections in permanent 95 positions for operation, bracing cables 23 are employed which are secured to one of the 100 rods 8 in front of one of the unions 5, as shown in Fig. 2, and these cables 23 are in turn secured to the connecting means 24. The inner end of each section is also braced 105 near one corner thereof, by means of bracing chains 25, which of course may be of any desired construction, and which will constitute an efficient brace for resisting any rearward movement of the sections supported upon the side of the vessel or the hull thereof. Suitable buffer blocks 26 are secured to the lower end of the frame 3 and are adapted 110 to abut against the hull 1 of the vessel and resist any inward pressure upon the sections of the protector. These buffer blocks 115 26 will constitute a very simple and efficient resilient support for the lower end of the sections or frame 2.

The buffer blocks 26 are adapted to be held normally out of contact with the hull 1, and are only brought into engagement when pressure is brought to bear upon the outer ends of the protector sections of the torpedo 120 guard.

A plurality of drums 27 are mounted 125 upon the deck of the hull 1, and these drums may be operated in any suitable position for winding the lifting cable 28 thereover, and lifting the protector sections to a vertical position. These protector sections are nor- 130

5 mally kept in a vertical position, while the ship is passing through a safe zone, but as soon as a ship is passing through a danger zone, these protector sections are lifted 10 down to an operative position. The lifting cable 28 is secured to each section in front of one of the unions, passing over the guiding pulley carried by the standard 30, upon the deck of the ship. A suitable pawl is 15 mounted upon a shaft 33 which may extend throughout the entire length of the hull of the vessel, and may operate in unison with suitable pawls engaging all of the drums 27. This is so constructed as to permit all of the 20 pawls 31 to be immediately operated in unison for the purpose of permitting the drums 27 to unwind and thereby allow the protector section or guard to drop to an operative position.

20 It of course should be understood that the protector sections are formed of "knock-down" structure in order to permit the structure to be readily assembled and parts thereof to be readily replaced, and in view 25 of this structure it should be understood that when the device is not desired for immediate use several parts of the guard may be readily disassembled and the same stowed away in a minimum amount of space. For instance, 30 the outer end may be readily removed from the frame, and the several parts of the frame may be readily separated.

35 By carefully considering Fig. 2, it will be seen that the shaft 33 carries an operating handle 34, which operating handle is adapted to permit all of the pawls 31 to be simultaneously released from the ratchet 32, and permit the drums or windlass 37 to unwind, and the sections of the protector or guard to 40 automatically drop to an operative position. It should be understood that all of the outer parts of the guard sections, such as the ends 11, etc., are rounded in order to prevent any sharp corners or obstructive parts to interfere with the effective operativeness of the 45 device.

50 A plurality of abutment knobs 30' are arranged along the side of the hull of the vessel 1, and are adapted to hold the protector sections away from the side of the hull, when the same are arranged to a vertical position. The abutment knobs 30' will act as buffers against which the upper side rods 2 of the protector sections will abut, when 55 the device is swung to its vertical position.

55 It should be understood that the protector sections 2 taper toward their rear or inner ends 35 or in other words have their rear ends slightly reduced in order to permit one 60 section to be removed from the ship without interfering with the other sections, should one of the sections need repairing. When the sections are removed, from the ship, it is necessary that the section be raised to a vertical position. It should further be under-

70 stood that all of these sections may be raised independently of the other sections, should it be so desired, as it is not necessary that all of the sections be raised simultaneously, or together. The structure of the sections showing the same tapered at their innerends 75 is clearly illustrated in Fig. 12 of the drawings.

75 It should be understood that certain detail changes may be made in the detail mechanical construction and the proportion of the device, without departing from the spirit of the invention.

80 As shown in Figs. 2 and 3 of the drawings, a turn buckle 25' may be carried there-by for the purpose of permitting the chain 25 to be adjusted or tightened.

85 What is claimed is:—

1. A torpedo guard of the class described, comprising a plurality of similarly constructed sections, each section comprising an inner frame, a plurality of outwardly extending rods, vertically extending bracing means interposed between said rods, an outer net frame carried by the outer ends of said rods, a yieldable cable net woven upon said net frame, and adapted to constitute a yieldable buffer for preventing the contact of a torpedo with the side of a ship carrying said guard, means for raising and lowering said sections and means for bracing said sections 90 against lateral swing.

95 2. A torpedo guard of the class described, comprising a plurality of similarly constructed sections, each section comprising an inner frame, a plurality of outwardly extending rods, vertically extending bracing means interposed between said rods, a yieldable cable net woven upon said end frame, and adapted to constitute a yieldable buffer for preventing the contact of a torpedo with the side of a ship carrying said guard, means for raising and lowering said sections, means for bracing said sections against lateral swing, hooks adapted to be carried by the 100 sides of a vessel, and eye bolts carried by said drums of said sections and fitting over said hooks for constituting a hooking connection for said sections.

105 3. A torpedo guard of the class described, comprising a plurality of similarly constructed sections, each section comprising an inner frame, a plurality of outwardly extending rods, vertically extending bracing means interposed between said rods, an 110 outer net frame carried by the outer ends of said rods, a yieldable cable net woven upon said net frame, and adapted to constitute a yieldable buffer for preventing the contact of a torpedo with the side of a ship carrying said guard, means for raising and lowering said sections, means for bracing said sections against lateral swing, hooks adapted to be carried by the sides of a vessel, and eye bolts carried by said drums of said sec- 115

- tions and fitting over said hooks for constituting a hooking connection for said sections, a yieldable buffer carried by the lower end of each section.
5. 4. A torpedo guard of the class described, comprising a plurality of sections, each section comprising a frame, a net supporting frame carried by the outer end of each frame, each net supporting frame provided with a cable, a reinforced woven net extending across the outer end of said frame and being provided with laterally extending flaps adapted to overhang a portion of the next adjoining section, for producing a
- 10

continuous yieldable net around the entire 15 hull of a vessel, and said net being woven to constitute a plurality of substantially diamond shaped pockets having knotted joints at their corners.

5. A torpedo guard comprising a plurality of sections, each section comprising an inner frame, and an outer protector frame, and each alternate outer protector frame, provided with laterally extending portions overhanging the adjoining frames. 20 25

In testimony whereof I hereunto affix my signature.

LOUIS MILLER.
